UNITED STATES PATENT OFFICE.

WOLF KRITCHEVSKY AND HAROLD C. PRUTSMAN, OF CHICAGO, ILLINOIS, ASSIGNEES
TO WILLIAM CITRON, TRUSTEE, OF CHICAGO, ILLINOIS.

DYE SOAP.

No Drawing.

Application filed May 5, 1926. Serial No. 106,862.

Our invention relates to chemicals for coloring fabrics, and particularly to a compound having the combined functions of a dye and a detergent.

5 A product consisting of a mixture of a dye and ordinary soap has been on the market for many years, the substance performing its combined functions in a partially satisfactory manner, but subject to numerous objections that are inherent in the materials employed. For example: When a compound such as described is used in a hard water solution, a scum will invariably form on the surface of the liquid especially after the addition of salt, and the particles composing the scum will adhere to the fabric and particularly to the seams thereof. This scum is formed due to the presence of lime, magnesium and other metallic salts in the hard water; the substance is in effect an insoluble metallic soap that is sticky, greasy and deleterious to garments. An effort has been made to overcome this defect by the use of a small quantity of sul- 25 phonated oil without effecting any appreciable improvement.

Another objection to the compound described is that the soap has the effect of preventing the dye from penetrating and adhering to the fabric and it is difficult or impossible to obtain heavy or saturated dyeing. This objection is particularly noticeable relative to heavy cotton fabrics, as the dye does not penetrate and the operation results in streaked or superficial dyeing. It is practically impossible to dye wool fabrics with the ordinary dye soaps as the dye does not penetrate, and rubs off.

40 One of the fundamental objections to a dye soap as at present manufactured and sold is its tendency to dry out while in the hands of dealers, the water evaporating as a natural consequence of exposure of the soap to the air, thereby rendering the product less soluble. Furthermore, dye soaps made from ordinary soaps have a great disadvantage of decomposing, and liberating free fatty acid, if they are mixed with dyes, which contain any percentage of free acid of the dye.

45 Our improvement contemplates the use of a soap that differs from that in ordinary use, that is composed of saponified fatty acids or oils. We employ a detergent which 55 is sulphonated soap, made of sulphonated

oils that have been saponified. A dye mixture with this material eliminates the defects and objections heretofore pointed out and is in commercial form fully as economically produced. When our compound 60 is used with hard water, it will not form a scum on the surface; the dye will penetrate all kinds of fabrics and avoid streaked or surface coloring; will give full shades with dark colors; will not dry out while in the 65 hands of dealers, and will not liberate fatty acid when combined with a dye that is partially or wholly a free acid. Sulphonated soaps are stable toward dilute acids, and also lime and magnesium salts present in 70 hard water, which is not the case with ordinary soaps.

The sulphonated soap differs radically from ordinary soap as well as from sulphonated oil. It is a distinct chemical unit 75 having the properties of both soap and sulphonated oil which properties cannot be duplicated in a mixture of common soap and sulphonated oil.

The acidic group of ordinary soap is a 80 carboxy group (COOH) the general formula of soap being: R—CO—OX, in which R represents any hydrocarbon radical or derivative thereof, and X any alkaline metal like sodium, potassium or ammonia.

85 Sulphonated oil, on the other hand, is the result of the treatment of castor or other oils with sulphuric acid, being a sulphonic acid derivative of the oil and the fat. In sulphonated oil, the acidic group is a sul- 90 phonic acid group and has the general formula: Y—R—SO₃X, Y representing the glycerine, R the hydrocarbon or derivative, and X any metal. Thus, there is no free carboxy group in the sulphonated oil as it is 95 esterified by glycerine, and there is no sulphonic acid group in common soap.

The sulphonated soap has both the carboxy group salt and the sulphonic acid group salt, the general formula being:

100 X representing any metal and R the hydrocarbon radical or its derivative. It is noted that both acid radicals are integral parts of 105 the compound and cannot be separated or split off without changing the characteristics of the finished product.

In the manufacture of the product, we melt, or grind without melting, a specified 110

- amount of sulphonated soap and add to this the necessary dye, the chemicals being mixed until uniform. Depending upon the proportions of dye and sulphonated soap, the product can be obtained either in powdered or paste form and can be produced either hot or cold. The ratio of the soap to the dye can be varied within a wide range, depending wholly upon the requirements of the finished product.
- It is not essential that previously prepared sulphonated soap be used, as it is possible to treat the required amount of sulphonated oil by adding to it the proper amount of alkali necessary to hydrolyze off the glycerine from the fatty acids. It is then heated until saponification is complete, and the dye, dye assistants, fillers, etc. are added.
- Besides dye and sulphonated soap, we may use other ingredients to assist in dyeing or to restrict the dye from attacking certain fabrics or to make it liquid or solid as desired. It can be combined with common salt, Glauber's salt, tartar emetic or other dye assistants, hydrocarbons, alcohol, or other organic compounds, or even a certain amount of plain soap or sulphonated oil to obtain the required consistency.
- The dye may be of different classes. We may use acid, basic or direct dyes, depending on whether the product is to be used to dye silk, cotton or mixed goods. Of course, the desired shades will be obtained by proper mixing of colors. Specific examples that have been found to be practical and satisfactory may be made up as follows, the proportions being by weight:
1. 30% sulphonated soap, 50% common salt, 20% direct black.
  2. 20% sulphonated soap, 5% fast red A, 75% ammonium sulphate.
  3. 10% sulphonated soap, 2% patent blue, 30% alcohol, 58% water.
  4. 95% sulphonated soap, 5% rhodamine B.
  5. 50% sulphonated soap, 5% cyanone blue R, 5% diazo black BH, 40% sodium lactate.
- It is understood that in the preparation of sulphonated soap, any of the commercial oils or fatty acids may be used. It is also understood that the examples given are merely instructive and not limitations as to the scope of the invention. The scope of the invention is indicated in the appended claims.
- We claim:
1. A dye soap comprising sulphonated soap, and dye.
  2. A dye soap comprising sulphonated soap, a dye and a dye assistant.
  3. A dye soap comprising sulphonated soap, a dye and a solvent.
  4. A dye soap comprising a sulphonated soap, a dye; and a filler.
  5. A dye soap consisting of a sulphonated soap, dye, dye assistant, solvent and filler.
  6. A dye soap consisting of a dye and a soap, the general formula of the soap being:

where R represents a hydrocarbon and X a metal.

In testimony whereof we have affixed our signatures.

WOLF KRITCHEVSKY.
HAROLD C. PRUTSMAN.
